(57) CLAIM

The ornamental design for a heater, as shown and described.

DESCRIPTION

FIG. 1 is a front perspective view of a heater showing my new design;

FIG. 2 is a top plan view thereof;

FIG. 3 is a right side view thereof; and,

FIG. 4 is a front view thereof.

The broken line shown in the drawings are for the purpose of illustrating portions of the article and form no part of the claimed design.

1 Claim, 4 Drawing Sheets

FIG. 1

FIG. 4
